A. B. Bowman
ATTORNEY

UNITED STATES PATENT OFFICE.

WILLIAM S. BING, OF SAN DIEGO, CALIFORNIA.

HOSPITAL-ROOM INDICATOR.

Application filed January 12, 1927. Serial No. 160,637.

My invention relates to a hospital room indicator, more particularly to indicators which may be placed on the outside of the door of the room so that outsiders may 5 know the requirements within, and the objects of my invention are: first, to provide a device of this class which combines the room number, quickly changeable room requirement indicator and physician's card 10 holder into one unit; second, to provide a device of this class which is a complete indicator for the outside of doors of hospital rooms; third, to provide a device of this class which is compact and neat in 15 appearance; fourth, to provide a device of this class which is simple in construction, and fifth, to provide a device of this class which is attractive, durable, and which will not readily deteriorate or get out of order. 20 With these and other objects in view, as will appear hereinafter, my invention consists of certain novel features of construction, combination and arrangement of parts and portions, as will be hereinafter 25 described in detail and particularly set forth in the appended claims, reference being had to the accompanying drawings and to the characters of reference thereon, which form a part of this application, in which: 30 Figure 1 is a front elevational view of my device; Fig. 2 is a sectional view thereof through 2-2 of Fig. 1, with parts and portions shown in elevation to facilitate the illustration; Fig. 3 is a sectional view 35 through 3-3 of Fig. 1, and Fig. 4 is an elevational view of the revolvable indicator member 3.

The casing 1, filler 2, indicator member 3, indicator member actuating means 4, physician's card holder member 5, and the screws 6, constitute the principal parts and portions of my invention. 40

The casing 1 is preferably made of light sheet metal with raised portions, such as 45 the numerals 1^a, designs 1^b, printing 1^c, screw holes 1^d, and an aperture 1^e in the casing, which exposes portions of the indicator member 3, as shown best in Fig. 1 of the drawings. 50

The edges of the casing 1 are folded back 55 against themselves at 1^f and clamp and support the filler 2. The filler 2 is preferably composed of suitable material, such as cardboard, and is provided with a cutout portion 2^a adapted to receive the indicator member 3. The indicator member 3 is preferably circular in shape and is provided with printing 3^a, which may be arranged as shown in Fig. 4 of the drawings. The indicator member is manually actuated by a 60 means 4, consisting of the knob 4^a, shaft 4^b and a washer 4^c. The shaft 4^b passes through a hole in the casing 1 and through the indicator member 3. The washer 4^c fits on the protruding end of the shaft and is 65 rigidly secured to the indicator member by means of points 4^d, which extend into the surface of said indicator member. The head of the shaft is riveted at 4^d, thus rigidly securing the washer 4^c to the shaft 4^b and 70 forcing the points 4^d into the indicator member 3. This indicator member is provided on one side with printing matter as follows: "Quiet," "No visitors," "Sleeping" 75 and "Limit visit to 5 min.," which is positioned to pass under the aperture 1^e, as shown, when the indicator is revolved. 80

Near the normally lower end of the casing 1 is a card holder 5, preferably made of wire, with looped portions 5^a at its extremities and a lug portion 5^b midway between the loops, as best shown in Figs. 1 and 3 of the drawings. A physician's card or the like may be slipped under the wire on either side of the lug 5^b. The card retainer 5 is held in place by means of screws 6, which pass through the loops 5^a, through the screw holes 1^d of the casing and through the filler. The upper portion of the casing is also held by screws 6, which pass through holes 1^d and through the filler, as shown best in Figs. 1 and 2 of the drawings. The device may thus be fastened to a door or any convenient place. The casing is provided on its outer surface above the card retainer with the words "Physician in attendance." 85

Though I have shown and described a particular construction, combination and arrangement of parts and portions, I do not wish to be limited to this particular 90

100

construction, combination and arrangement, but desire to include in the scope of my invention, the construction, combination and arrangement substantially as set forth in 5 the appended claim.

Having thus described my invention, what I claim as new and desire to secure by Letters Patent is:

In a device of the class described, a 10 revoluble indicator member, a hollow casting in which said indicator member is revolvably mounted, and means for revolving said revoluble member including a knob provided with a shank extending there- 15 through, and a washer member mounted on the opposite side of said shank provided with inwardly extending portions engag- ing said revoluble member.

In testimony whereof, I have hereunto 20 set my hand at San Diego, California, this 24th day of December, 1926.

WILLIAM S. BING.
